UNITED STATES PATENT OFFICE.

WILLIAM T. BATE, OF CONSHOHOCKEN, PENNSYLVANIA.

LOW-WATER ALARM.

SPECIFICATION forming part of Letters Patent No. 291,272, dated January 1, 1884.

Application filed November 6, 1882. (No model.)

To all whom it may concern:

Be it known that I, WILLIAM T. BATE, a citizen of the United States, and a resident of Conshohocken, Montgomery county, Pennsylvania, have invented certain Improvements in Low-Water Alarms for Steam-Boilers, of which the following is a specification.

My invention relates to an improvement in that class of low-water alarms or boiler-feeders in which the whistle or feed valve is under the control of a float in a vessel communicating with the boiler, the objects of my invention being to construct an effective device of this class, and to provide for the sounding 15 of an alarm or the control of the water-supply upon an undue movement of the float in either direction.

In the accompanying drawings, Figure 1 is a side view, partly in section, of my invention applied to an alarm for steam-boilers; Fig. 2, an enlarged perspective view of part of the same, and Fig. 3 a view showing a modification of one of the features of the invention.

25 A is a vessel, of any suitable size and shape, communicating at the upper end with the steam-space of the boiler through a valved pipe, a, and at the lower end with the water-space of the boiler through a valved pipe, b, so that the water in the vessel A is always maintained at the same level as that in the boiler.

Within the vessel A is a hollow float, B, from which projects a tubular stem, d, the latter passing through a stuffing-box on the top of the vessel A, and being guided at the upper end in a bracket, e, secured to a post, E, projecting from the said vessel A.

To the stem d are secured two tappets, f and g, each having a projecting finger, the end of which is adapted to a slot in the post E, so that the tappets are prevented from turning on the stem d.

On the steam-pipe a is a branch, h, carrying a steam-whistle, F, of ordinary construction, and on the valve-casing of the whistle are projecting arms i i, to which are hung two bell-crank levers, m and n. The long arm of each lever carries a roller, p, and the short arm of the lever m is adapted to bear upon the end of the valve-stem w, the short

arm of the lever n being forked, so as to embrace the stem w, and being adapted to bear upon a shoulder formed upon said stem. As the water-level in the boiler rises or falls, 55 there is a like change in the level of the water in the vessel, A, and a rising-and-falling movement of the float B. Should the float fall to an undue extent, the tappet f comes into contact with the roller p of the lever m, and actuates the latter so as to impart an inward thrust to the valve-stem, thereby opening the valve and causing the sounding of the whistle. Should the float rise above the proper height, the same result will be effected through the 65 medium of the tappet g and lever n. By properly adjusting the tappets f and g in respect to each other on the stem d, any desired amount of rise and fall of the float B may be permitted before the alarm is sounded. 70

Instead of using two tappets, f and g, a single tappet may be used, as shown in Fig. 3, said tappet being adapted to act directly upon the lever m, but acting upon the lever n through the medium of a guided rod, x, to a 75 slot in which the tappet is adapted.

In place of or in addition to operating the whistle-valve, the device may be employed to operate the valve in the feed-pipe of the boiler, and when it is not desired to indicate an undue rise in the water-level, the lever n and the devices for operating the same may be dispensed with. A solid stem may be used in place of the tubular stem d; but the latter is preferred, as it prevents the accumulation in the float B of water which may gain access thereto, the water being vaporized, and the vapor escaping through the said tubular stem. 80 85

In the present instance I have shown the vessel A as provided with the water-gage usually attached to the head of the boiler. The gage-cocks may also be applied to the vessel A, and the formation of a number of openings in the head of the boiler thus rendered 90 unnecessary. 95

I claim as my invention—

1. The combination of the vessel A, communicating with the steam and water spaces of the boiler, the float B, having a stem, d, 100 with an adjustable tappet, f, and alarm-whistle and its valve, and a lever, m, adapted

to act directly upon the stem of the valve, and projecting into the path of the tappet *f*, as set forth.

2. The combination of the whistle-valve *g* having a stem, *w*, two levers, *m* and *n*, both adapted to act directly upon said stem, the vessel *A*, and a float, *B*, having a stem, *d*, with tappet or tappets for actuating the levers *m* and *n*, as set forth.

In testimony whereof I have signed my name to this specification in the presence of two subscribing witnesses.

WILLIAM T. BATE.
